PAIR OF SAFETY SPECTACLES AND HEADBAND COMBINATION

Jack N. Simpson, Reading, Pa., assignor to The Electric
Storage Battery Company, Philadelphia, Pa.

Filed Nov. 22, 1965, Ser. No. 88,166

Term of patent 14 years

(Cl. D57—1)

Fig. 1

Fig. 5.

FIG. 1 is a top perspective view of a pair of safety spectacles and headband combination showing my new design;

FIGS. 2, 3 and 4 are front, top and side views, respectively, thereof; and,

FIG. 5 is a cross-sectional view taken along line V—V of FIG. 1.

The side not shown has substantially the same appearance as the side shown, except the temple is flat and plain.

The dominant features of my design reside in the portions shown in full lines.

I claim:

The ornamental design for a pair of safety spectacles and headband combination, substantially as shown and described.
